(57) **CLAIM**

The ornamental design for a ski pole handle, as shown and
described.

DESCRIPTION

FIG. 1 is a front elevational view of a ski pole handle
showing my new design. The broken lines are for illustrative
purposes only and form no part of the claimed design;

FIG. 2 is a right side elevational view thereof;

FIG. 3 is a perspective view thereof; and,

FIG. 4 is a left side elevational view thereof.
